6-ALKYLDIOSGENINS, AND DEGRADATION
TO DICSONESBjarte Löken, Roosevelt, and Hector Flores, San Juan,
Puerto Rico, assignors to G. D. Searle & Co., Chicago,
Ill., a corporation of DelawareNo Drawing. Application May 27, 1958
Serial No. 738,007

4 Claims. (Cl. 260—239.55)

The present invention relates to a novel method for the preparation of a group of steroid intermediates. In particular it relates to a process of degrading 6-alkylated sapogenins to 6α -alkyl- 16β -(δ -acetoxy- γ -methylpentanoyloxy)-4-pregnene-3,20-dione and therefrom to 6α -alkyl-4,16-pregnadiene-3,20-diones. The latter, which are the subject matter of a separate application, can be converted to 6α -alkyl- 17α -acetoxy-4-pregnene-3,20-diones which are highly active progestational agents. A typical method for the conversion of the 6α -alkyl-4,16-pregnadiene-3,20-diones to progestationally active compounds is given in one of the examples.

The processes of this invention follow the general reaction sequence illustrated in the following table in which R can represent hydrogen or a lower alkyl radical.

From diosgenin there is prepared 6β -alkyl-22-isooallospirostane-3 β ,5 α -diol (I), a compound of a type which is also disclosed in a copending application by Miramontes, Romero, and Ahuad, Serial No. 686,562, filed September 27, 1957. This diol (I) is next oxidized to the 5α -hydroxy- 6β -alkyl-22-isooallospirostan-3-one (II). Treatment with alkali yields the 6α -alkyl-22-iso-4-spirostan-3-one (III). In the following isomerization reaction, compounds of type II or III can both be used. When the 5α -hydroxy- 6β -alkyl-22-isooallospirostan-3-one is heated under isomerizing conditions in an excess of acetic anhydride, a molecule of water is formed in the course of the dehydration reaction, and this molecule of water reacts with the acetic anhydride to form 2 molecules of acetic acid; however, the dilution of the acetic anhydride by the acetic acid so formed has no detrimental effect upon the efficiency of the over-all reaction. The resulting 3,26-diacetoxy-6-alkyl-3,5,20(22)-furostatriene (IV) is next hydrolyzed with strong alkali (e. g. caustic soda or potash) in a lower alkanol, suitably methanol, to saponify both the enolic acetate group and the 26-acetoxy group so as to form the 6α -alkyl-26-hydroxy-4,20(22)-furostadien-3-one (V). The compound V is reacetylated with acetic anhydride in a strong organic base (typically in pyridine or an alkylated pyridine such as lutidine, picoline and collidine, or in aniline), to yield a 26-acetate (VI), which is then oxidized with chromic acid to yield the 6α -alkyl- 16β -(δ -acetoxy- γ -methylpentanoyloxy)-4-pregnene-3,20-dione (VII). This ester is then saponified and dehydrated with alkali to yield the 6α -alkyl-4,16-pregnadiene-3,20-dione.

While the 6α -alkyl derivatives are of particular interest, the process is likewise applicable for the preparation of the unsubstituted 4,16-pregnadiene-3,20-dione in which R is hydrogen, and which is useful as starting material for such compounds as 17,21-dihydroxyprogesterone.

2

A well-known procedure for the degradation of diosgenin and other sapogenins (Marker, J. A. C. S. 1940, p. 2526), describes the chromic acid oxidation of the compound of the type IV to the type VII. This procedure gives very low yields in the case of the compounds in which R is hydrogen and fails practically completely with the 6α -alkyl derivatives.

Applicants have now found that the undesirable side reactions which occur in the direct oxidation of compounds of the type IV to those of type VII can be avoided, and 40 to 45% yields, by weight, can be achieved in the conversions of the compounds of the type III all the way to the compounds of the type of VIII by the intermediate preparation of the compounds of the type V and VI. The high yields are obtained because the complete isolation of the compounds of the type IV, V, VI, and VII is unnecessary under the experimental conditions employed in the new process described herein. It is a special advantage of this reaction sequence that costly purification procedures, such as recrystallizations or chromatography, are not required.

The invention will be described in further detail in the following examples, but these are not to be construed as limiting the invention in spirit or in scope. It will be apparent to those skilled in the art that numerous modifications in materials and methods can be adopted without departing from the scope of the invention. In the examples quantities are indicated as parts by weight.

Example 1

A solution of 100 parts of diosgenin in 1340 parts of dichloromethane is treated under ice cooling with a solution containing 160 parts acetone, 270 parts of dichloromethane, 2 parts of sodium acetate, and 70 parts of commercial peroxyacetic acid. The mixture is then maintained at room temperature for 5 hours and at the end of that time washed with 1000 parts of a 5% ferrous sulfate solution to reduce the excess peroxyacetic acid. The organic layer is separated and washed with water, and the washings are reextracted with dichloromethane. The organic extracts are combined and concentrated to dryness on a steam bath, and then 800 parts of heptane are added, and a small head fraction is distilled off in order to remove residual dichloromethane. The mixture is cooled to 30° C. under agitation, and the crystalline material is collected on a filter. This crystalline material consists predominantly of $5\alpha,6\alpha$ -epoxy-22-isoallospirostan-3 β -ol. The mother liquor is evaporated to a small volume, and a second crop is harvested, which is also a mixture of 2 epimeric epoxides containing mainly the β -epoxide. The first crop is dissolved in dichloromethane and then treated with 1300 parts of heptane, and the mixture is distilled to remove the dichloromethane. Upon complete removal of the dichloromethane, almost pure $5\alpha,6\alpha$ -epoxy-22-isoallospirostan-3 β -ol is obtained, melting at about 225–227° C. A solution of 150 parts of this epoxide in 2700 parts of toluene is slowly added to 1500 parts of a 3-molar commercial solution of methylmagnesium bromide. The mixture is then refluxed for 150 minutes, chilled, and treated with water until no more reaction can be observed. It is then subjected to steam distillation, and the residual suspension is cooled and treated with a mixture of 480 parts of concentrated hydrochloric acid and 400 parts of water. The crude product is collected on a filter, washed and dried. It is then dissolved with dichloromethane, treated with activated charcoal, and filtered through a filter aid. The clear filtrate is concentrated to a small volume and methanol is added. The mixture is then distilled until all dichloromethane has been removed and until crystallization begins. Upon cooling, the product crystallizes and, on recrystallization from methanol, there is obtained 6β -methyl-22-isoallospirostan-3 $\beta,5\alpha$ -diol which melts at about 226.5–230° C. The rotation in chloroform α_D is -85° .

Substitution of an equimolar equivalent of ethylmagnesium bromide for the methylmagnesium bromide in the foregoing reaction yields the 6β -ethyl-22-isoallospirostan-3 $\beta,5\alpha$ -diol.

Example 2

To an agitated suspension of 55.5 parts of 6β -methyl-22-isoallospirostan-3 $\beta,5\alpha$ -diol in 880 parts of acetone, which is cooled to 15° C., is added in small portions in the course of 45 minutes a solution of 14.8 parts of chromium trioxide in 27 parts of water containing 5 parts of sulfuric acid, the temperature being allowed to rise to 25° C. Agitation is then continued for 90 minutes,

after which 2300 parts of ice water are added and the resulting precipitate is collected on a filter, washed with much water, and then with a 1% aqueous sodium bicarbonate solution, and finally, again with water. The 5α -hydroxy- 6β -methyl-22-isoallospirostan-3-one thus prepared is sufficiently pure for use in the procedure of the next two examples. On recrystallization from equal parts of dichloromethane and acetone, a melting point of 244.5-246° C. is obtained. The rotation α_D in chloroform is -75°.

Example 3

A suspension of 43 parts of 5α -hydroxy- 6β -methyl-22-isoallospirostan-3-one in 98 parts of acetic anhydride is heated in a sealed tube at 195° C. for 6 hours, after which the contents are cooled, and 40 parts of pyridine are added. The solution is precipitated in a large volume of ice water under agitation, and the resulting mixture is agitated for 3 hours. The aqueous phase is then removed, and the oily residue is repeatedly extracted with water. The residue consists predominantly of 6-methyl-3,26-diacetoxyl-3,5,20(22)-furostatriene.

To the crude 6-methyl-3,26-diacetoxyl-3,5,20(22)-furostatriene thus obtained is added a solution of 20 parts of potassium hydroxide in 30 parts of water and 150 parts of methanol. This mixture is heated for 45 minutes under reflux with efficient agitation. The resulting 6 α -methyl-26-hydroxy-4,20(22)-furostadien-3-one is precipitated by pouring the reaction product resulting from the saponification into 1000 parts of ice water with agitation. The mixture is then permitted to settle and the aqueous phase is decanted. The oily residue is washed repeatedly with water at 50° C. Prior to each decantation it is found advisable to cool the mixture by the addition of ice. The final residue, which has an almost solid consistency, is spread on a ceramic dish for air drying. The dried material is then transferred into a reaction vessel, the ceramic dish is extracted with 45 parts of pyridine, and the extracts are added to the reaction vessel. Finally 44 parts of acetic anhydride are added, and the mixture is maintained at 60° C. for 45 minutes. The 6 α -methyl-26-acetoxyl-4,20(22)-furostadien-3-one thus obtained is precipitated by addition to 1000 parts of ice water. After settling, the aqueous phase is decanted, and the residue is once more washed with water.

The residue is then transferred with 240 parts of dichloromethane into a reaction vessel to which are added 190 parts of glacial acetic acid. Ten parts of water are added to remove any residue of acetic anhydride. The solution thus obtained is cooled to 5° C. and treated by slow addition with a solution of 18 parts of chromium trioxide in 25 parts of water and 20 parts of acetic acid while the mixture is efficiently stirred. In the course of the addition, which takes about 45 minutes, the temperature is permitted to rise to about 12° C. Agitation is continued for 3 hours at a temperature of about 20 to 25° C. after which water is added. Further addition of a saturated solution of sodium chloride permits a convenient separation. The aqueous layer is separated and reextracted with dichloromethane, and the combined organic extracts, which are usually green but occasionally bluish-violet in color, are taken to dryness on a steambath. Water is twice added to the residue and distilled off in vacuum to remove residual solvents.

To the 6 α -methyl-16 β -(δ -acetoxyl- γ -methylpentanoyloxy)-4-pregnene-3,20-dione thus obtained there are added 190 parts of acetone, and heat is applied until complete solution results. A solution of 15 parts of sodium hydroxide in 240 parts of water is then added, and the mixture is maintained at 45-50° C. for 15 minutes. The reaction mixture is cooled to 0° C. and the resulting precipitate is collected on a filter and washed with a 13:7 mixture of acetone and water. A mixture of 28 parts of the crude product in 280 parts of acetone is stirred at 25° C. The chromium salts are removed by

filtration through a bed of filter aid, and the filtrate is taken to dryness on a steambath. The residue is taken up in methanol, and chilled to yield crystals of 6 α -methyl-4,16-pregnadiene-3,20-dione, melting at about 175-180° C. The rotation of a chloroform solution α_D is 152°.

Example 4

In a mixture of 2.3 parts of potassium hydroxide, 5 parts of water, and 320 parts of methanol, there are suspended 20 parts of 5α -hydroxy- 6β -methyl-22-isoallospirostan-3-one, and the mixture is refluxed for 10 minutes. Then 500 parts of water are added and the mixture is cooled, and a solid material is collected on a filter and washed with water to neutrality to yield 6 α -methyl-22-iso-4-spirostan-3-one which, recrystallized from methanol, melts at about 211-213° C. The rotation of α_D in chloroform is -28°. The molecular absorption coefficient at 241 millimicrons is about 17,000.

A mixture of 40 parts of this compound with 98 parts of acetic anhydride is heated at 195° C. for 6 hours, and further treated as in the reaction sequence in the preceding example, to yield 6 α -methyl-16-dehydroprogesterone in essentially the same yield. As a variation, 1,2-dichloroethane can be used in lieu of dichloromethane.

Example 5

On substitution of 60 parts of 6β -ethyl-22-isoallospirostan-3 β ,5 α -diol as a starting material in Example 2, and use of procedures of Examples 2 and 3, there are obtained sequentially 6-ethyl-3,26-diacetoxyl-3,5,20(22)-furostatriene, 6 α -ethyl-26-hydroxy-4,20(22)-furostadien-3-one and its 26-acetate, 6 α -methyl-16 β -(δ -acetoxyl- γ -methylpentanoyloxy)-4-pregnene-3,20-dione, and finally 6 α -ethyl-4,16-pregnadiene-3,20-dione. An ultraviolet maximum is observed at 241 millimicrons with a molecular extinction of about 25,000.

Example 6

A solution of 10 parts of 6 α -methyl-4,16-pregnadien-20-one in 360 parts of pure methanol is cooled to 8° C., and at that temperature treated by slow addition with 21.5 parts of a 35% aqueous hydrogen peroxide solution and 3.85 parts of a normal aqueous sodium hydroxide solution with continuous agitation. The reaction mixture is then maintained for 9 hours at about -2° C. after which 0.26 part of glacial acetic acid is added. The neutralized methanolic solution is filtered, and the filtrate is diluted with water to precipitate the 6 α -methyl-16 α ,17 α -epoxyprogesterone.

To 5 parts of this epoxide in 10 parts of glacial acetic acid is added a saturated solution of hydrogen bromide in 7 parts of glacial acetic acid, and the mixture is permitted to stand at room temperature for 30 minutes. The mixture is then poured into ice water, and the bromohydrin is extracted with ether. Upon evaporation of the ether, the dry bromohydrin is refluxed for 2 hours in methanolic solution with twice its weight of Raney nickel. The Raney nickel is removed by filtration, and the methanolic solution is evaporated almost to dryness. On recrystallization from aqueous acetone, the 6 α -methyl-17 α -hydroxy-4-pregnene-3,20-dione thus obtained melts at about 211-213° C. Acylation by conventional procedure of such 6 α -alkyl-17 α -hydroxy-4-pregnene-3,20-diones yields highly potent progestational agents.

Example 7

A mixture of 40 parts of 22-iso-4-spirostan-3-one and 98 parts of acetic anhydride is heated at 195° C. for 6 hours, and thereafter worked up as in Example 3 to afford a high yield of 4,16-pregnadiene-3,20-dione, melting at about 186-189° C.

What is claimed is:

1. In the preparation of a member of the class consisting of 16 β -(δ -acetoxyl- γ -methylpentanoyloxy)-4-pregnene-3,20-dione and its lower 6 α -alkyl derivatives wherein

the lower alkyl group contains less than 3 carbon atoms, the step of heating the corresponding member of the class consisting of 3,26-diacetoxy-3,5,20(22)-furostatriene and its lower 6-alkyl derivatives with strong alkali in a lower alkanol, followed by contacting the resulting member of the class consisting of 26-hydroxy-4,20(22)-furostadien-3-one and its 6-lower alkyl derivatives with acetic anhydride, and contacting the resulting 26-acetate with chromium trioxide.

2. In the preparation of 6α -methyl-16 β -(δ -acetoxy- γ -methylpentanoyloxy)-4-pregnene-3,20-dione, the step of heating 6-methyl-3,26-diacetoxy-3,5,20(22)-furostatriene with strong alkali in a lower alkanol, followed by con-

5 tacting the resulting 6α -methyl-26-hydroxy-4,20(22)-furostadiene-3-one with acetic anhydride, and then contacting the resulting 26-acetate with chromium trioxide.

3. A process according to claim 2, wherein the acetic anhydride is used in pyridine solution.

4. 5α -hydroxy- 6β -methyl-22-isopriostan-3-one.
